UNITED STATES PATENT OFFICE

136,227

DESIGN FOR AN INSOLE

Wallace C. Wright, Brookfield, N. H.

Application April 10, 1943, Serial No. 109,951

Term of patent 14 years

To all whom it may concern:

Be it known that I, Wallace C. Wright, a citizen of the United States and a resident of Brookfield, county of Carroll, and State of New Hampshire, have invented a new, original, and ornamental Design for an Insole, of which the following is a specification, reference being made to the accompanying drawing, forming part thereof.

In the drawing:

Fig. 1 is a plan view of an insole, showing my new design;

Fig. 2 is a cross-sectional view on the line 2—2 of Fig. 1 showing the stitch-retaining rib for inseam attachment; and

Fig. 3 is a bottom view in perspective of my insole, showing the sewing rib with pinked attaching flange.

My design for an insole is characterized by the flexible leather insole blank and a sewing rib substantially in the configuration as shown, with pinked attaching flange adhesively secured to the leather insole.

I claim:

The ornamental design for an insole, substantially as shown and described.

WALLACE C. WRIGHT.
